(57) **CLAIM**

We claim the ornamental design for a damper, as shown and described.

DESCRIPTION

FIG. 1 is a front perspective view from above of the damper according to one embodiment;

FIG. 2 is a rear perspective view thereof;

FIG. 3 is a top view thereof;

FIG. 4 is a bottom view thereof;

FIG. 5 is a front view thereof;

FIG. 6 is a left side view thereof;

FIG. 7 is a right side view thereof;

FIG. 8 is a rear side view thereof;

FIG. 9 is a section view thereof along line 9-9 in FIG. 3;

FIG. 10 is a front perspective view from above of the damper according to another embodiment;

FIG. 11 is a rear perspective view thereof;

FIG. 12 is a top view thereof;

FIG. 13 is a bottom view thereof;

FIG. 14 is a front view thereof;

FIG. 15 is a left side view thereof;

FIG. 16 is a right side view thereof;

FIG. 17 is a rear side view thereof; and,

FIG. 18 is a section view thereof along line 18-18 of FIG. 12. The broken lines illustrate portions of the damper that form no part of the claimed design.
